CLAIM

The ornamental design for an enclosure for a sharps container, as shown and described.

DESCRIPTION

FIG. 1 is a perspective view of an enclosure for a sharps container.

FIG. 2 is a front view of the enclosure illustrated in FIG. 1. FIG. 3 is a right side view of the enclosure illustrated in FIG. 1.

FIG. 4 is a left side view of the enclosure illustrated in FIG. 1.

FIG. 5 is a rear view of the enclosure illustrated in FIG. 1. FIG. 6 is a top view of the enclosure illustrated in FIG. 1; and,

FIG. 7 is a bottom view of the enclosure illustrated in FIG. 1.

The features indicated in the figures in broken lines form no part of the claimed design.
